INKING DEVICE FOR PRINTING MACHINES

APPLICATION FILED DEC. 13, 1913.

Patented Oct. 22, 1918.

3 SHEETS—SHEET 3.

UNITED STATES PATENT OFFICE.

ARTHUR D. SABORSKY, OF LAKEWOOD, OHIO, ASSIGNOR, BY MESNE ASSIGNMENTS, TO THE ADVANCE MANUFACTURING COMPANY, OF DETROIT, MICHIGAN, A CORPORATION OF MAINE.

INKING DEVICE FOR PRINTING-MACHINES.

1,282,466.

Specification of Letters Patent.

Patented Oct. 22, 1918.

Application filed December 13, 1913. Serial No. 806,460.

To all whom it may concern:

Be it known that I, ARTHUR D. SABORSKY, a subject of Austria, and resident of Lakewood, in the county of Cuyahoga and State 5 of Ohio, have invented certain new and useful Improvements in Inking Devices for Printing Machines, of which I hereby declare the following to be a full, clear, and exact description, such as will enable others 10 skilled in the art to which it appertains to make and use the same.

This invention relates to an inking mechanism for a printing machine, particularly mechanism adapted to ink type or printing 15 devices mounted on a drum or cylinder or other suitable support.

One object of the invention is to provide mechanism for supplying ink to the ink distributing member.

20 Another object of the invention is to provide means for controlling the discharge or flow of the ink from the ink fountain, whereby any desired amount of ink can be supplied to the ink distributing member.

25 With these and other objects in view, the invention consists of the parts or combination of parts hereinafter set forth.

In the drawings, Figure 1 is a side elevation of an inking mechanism, embodying my 30 invention, and part of a printing machine to which the inking mechanism may be applied.

Fig. 2 is a side elevation looking at the mechanism from the other side and showing 35 the manner of adjustably mounting the several rolls; Fig. 3 is a transverse section of the rolls and fountain; Fig. 4 is a plan view of the inking mechanism; Fig. 5 is a side elevation of the oscillating roll, Fig. 6 is a 40 view partly in section showing the manner of mounting the fountain roll; Fig. 7 is an end view thereof; Fig. 8 is an elevation of the shifting rolls and the driving means therefor.

45 In these views A is a printing cylinder, which is adapted to be rotated in any suitable manner, and B, B, are side frames attached at D, D, to the frame C of a suitable printing press or machine.

50 In these frames B, B, the several rolls are mounted. E, E' indicate a pair of rolls which are preferably formed of steel and G, G', indicate a pair of rolls which may be formed from some suitable elastic composition.

These rolls E, E' have polished surfaces and 55 engage the elastic composition rolls G, G', while the latter contact with the cylinder, being suitably spaced apart to distribute the ink evenly thereon. F², F⁴, indicate gears, fixed to the rolls E', E, respectively. The 60 gears F², F⁴, together with suitably mounted gears F', F³, and F (which is fixed to the cylinder A) form a gear train by means of which the rolls E, E', are rotated.

The steel rolls are preferably of smaller 65 diameter than the composition rolls, and therefore rotate several times to one rotation of the composition rolls.

The steel roll E first receives the ink and applies it to the composition roll G. The 70 roll G in turn applies the ink to the second steel roll E', which distributes it over the second composition roll G'. The proportions of these rolls relatively to each other can be determined by their action in use. The composition rolls are preferably mounted in adjustable bearings H, and H' controlled by the eccentrics I, I', to exert the desired amount of pressure upon the cylinder and 75 steel rolls.

The steel rolls E, E', are, during operation of the press, preferably reciprocated or moved longitudinally of their axes for a purpose well known to those skilled in the art to which my invention relates. This movement may be effected by means of rock arms J, J' mounted upon a shaft K and a slotted arm K' and crank K² fixed to a shaft K³, the opposite ends of which have bearing in supports k, k'. The shaft K³ is preferably provided with a worm wheel K⁴ meshing with a worm K⁵ which may be fixed to the shaft K⁶ of one of the reciprocating or driven rolls E, E'. 80 85 90

This constant shifting of the positions of 95 these steel rolls serves to distribute the ink more evenly over the surface of the composition rolls, G, G'.

L indicates a fountain roll which may be formed of any suitable material, such as 100 steel. The roll L is preferably rotated relatively slow by means of the worm L' upon the shaft K³ and a worm wheel L² upon the shaft L³ of the fountain roll.

The roll L receives ink in the form of a 105 film distributed upon its polished surface by means of a blade M, which may be relatively thin and formed of steel. The blade M may

be mounted between the side frames B, B, upon a bar N which is detachably secured in the cross bar N' by screws N⁶.

Set screws N², N² arranged at regular intervals in the bar N' may be provided to press upon the lower edge of the steel blade M, and adjust with the greatest nicety the distance of its free edge from the surface of the roller L. As the blade M is relatively thin, it will spring enough to permit one portion of its free edge to be brought nearer the roll than another so that the thickness of the coating or film distributed on the roll L can be regulated either along the entire roll or any part or parts thereof.

O indicates a device for conveying the ink from the fountain roll to the first one of steel shifting rolls. The device O preferably comprises a roll formed from a suitable composition. The roll O is mounted to oscillate or swing freely between the fountain roll L and the adjacent shifting roll E.

This is accomplished by mounting the oscillating and conveying roll O upon a frame O' which is pivoted at O² in the side frames. Two cams O³, O⁴ alternately engaging the pin O⁶ upon the frame O' give alternately forward and rearward movement to the roll. The cams rotate with the shaft K² and the duration of time in which the roll is making contact with the fountain roll L and the adjacent shifting roll E can be adjusted by rotating one of the cams on its axis, and securing it by means of a set screw O⁴.

Thus the oscillating roll O can be made to contact for a longer period of time with one roll than with the other as desired and as the distribution of ink may require.

The roll O is an idler and hence will revolve rapidly when in contact with the steel roll E and more slowly when in contact with the fountain roll L, since its speed will correspond with the speed of the roll it makes contact with.

O⁵ indicates a spring, preferably of the coiled type, having one end connected to a cross bar O⁸ and its opposite end connected at o to the support O'. The connection o between the spring O⁵ and the support O' is preferably arranged on that side of the pivot O² remote from the bar O⁸, so that the spring, which is normally active, will tend to swing the support O' about its pivot O² in one direction or the other whenever the support is moved by the cams O³, O⁴, to bring the connection o to one side of a line cutting the axes of the pivot O² and bar O⁸. This construction and operation will be clearly understood from Fig. 3. As the spring O⁵ serves to swing the support O' laterally to cause engagement of the roll O with either roll E or L, after the roll L has been disengaged from the other roll, E or L, the roll O will always engage these rolls yieldingly. The resilient pressure

thus obtained compels contact of the conveyer roll under modifications in size of the rolls due to wear or shrinkage.

The inking fountain has for its walls the adjustable blade M on the front side and the fountain roller L upon the rear, and at its ends plates P, P, which are pressed against the opposite ends of the roll and blade M so as to completely close or bridge the openings or spaces therebetween.

The free ends of the plates P are preferably cut away on the arc of a circle to engage reduced ends of the fountain roll L, as shown in Figs. 3 and 4.

S, S, indicate springs each provided with a point or device s, which bears upon or engages the adjacent plate P, preferably at or near its center of gravity, to maintain the plate against the adjacent end of the roll L. S', S', indicate thumb screws which engage the springs S and serve to adjust the tension thereof against the plates P.

The springs and plates are preferably enclosed in openings between the side frames and ends of the transverse bar.

This method of forming the inking fountain prevents any leakage and dripping of ink and is very easy to clean since the plates and blade can readily be taken out, and no grinding of the curved surfaces is necessary to make the joints tight. The device is therefore economical to manufacture and simple in construction.

The fountain roll L is also easily removed to be cleaned. The roll L may be provided with a tapered self centering bearing W which enters a tapered socket in the sleeve W' upon which the worm wheel is mounted.

A pin X enters one of the grooves X' in the tapered bearing and rotates the roll. The thumb screw X² is inserted through the bearing W' and frame B as shown in Fig. 6. This screw supplemented by the similar thumb screw X³ at the other end of the roll L retains the roll in place and permits its removal for cleaning if desired.

To those skilled in the art, many alterations in construction and widely differing embodiments and applications of my invention will suggest themselves, without departing from the spirit and scope thereof. My disclosures and the description herein are purely illustrative and are not intended to be in any sense limiting.

Having described the invention what I claim as new and desire to secure by Letters Patent is:

1. The combination with a frame and spaced fountain and distributing rolls rotatably mounted thereon, of a conveyer roll intermediate of said fountain and distributing rolls, an oscillable support for said conveyer roll, means for oscillating said support to move said conveyer roll alternately in the direction of said fountain and distributor.

- rolls; and a spring connected to said support and serving to swing it laterally to alternately engage said conveyer roll with said fountain and distributor rolls and to hold the same in resilient contact therewith.
2. In an inking mechanism, the combination of an idler distributing roll arranged to make contact with a printing cylinder, a driven roll arranged to make contact with said distributing roll, a fountain roll, a conveyer roll adapted alternately to make contact with said fountain roll and with said driven roll, oppositely acting cams arranged to move said conveyer roll into engagement with said fountain roll and said driven roll, a spring for maintaining said conveyer roll in engagement with either of said fountain or distributing rolls, and means for adjusting one of said cams.
3. In an inking mechanism, the combination with a distributing roll and a fountain roll, of a conveyer roll adapted to remove ink from said fountain roll and apply it to said distributing roll, cams operating in opposite directions for giving an oscillating movement to said conveyer roll, and a spring acting to yieldingly press said conveyer roll in turn upon the fountain and distributing rolls.
4. In an inking mechanism, the combination with a frame, of a fountain roll and a distributing roll mounted in said frame, an ink conveyer member adapted to make contact alternately with said rolls, a pivoted support for said ink conveyer member, means for oscillating said support about its pivot, and a spring acting to press said ink conveyer member against either of said rolls when said support has been moved in one direction or the other by said oscillating means, said spring being connected to said frame.
5. In an inking mechanism, the combination with a frame, of a fountain roll and a shifting and distributing roll mounted in said frame, of an oscillatable support pivoted in said frame, a conveyer roll rotatably mounted therein, a shaft, cams upon said shaft adapted to engage and oscillate said pivoted support, and a spring engaging said support to hold said conveyer roll alternately in engagement with said fountain and distributing rolls.
6. In an inking mechanism, the combination of a fountain roll, a blade, a pair of end plates, said roll, blade and end plates coöperating to form the walls of a fountain, means for supporting one end of each plate, and a spring engaging each plate to hold its opposite end yieldingly against the adjacent end of said roll.
7. In an inking mechanism, the combination with a fountain roll forming one side of a fountain, and of an adjustable blade forming the other side of the fountain, a support for the blade, spaced adjusting means in said support, plates engaging the ends of said roll, plates, and means for adjusting the tension of said springs.
8. In an inking mechanism, the combination of a roll arranged to form one side of an ink fountain, supports for said roll, a transverse bar extending between said supports, an inclined blade forming the opposite side of the fountain, a support for said blade secured to said transverse bar, spaced adjusting devices in said bar engaging said blade, plates coöperating with said roll and blade to form the end walls of the fountain, springs for holding said plates in position, and means for adjusting said springs.
9. The combination of a distributing roll, a fountain roll, a swingably mounted rotatable member arranged to alternately engage said distributing and fountain rolls, means tending to move said swingably mounted member into engagement with either of said distributing and fountain rolls, and means for disengaging said swingably mounted member from one of said rolls to permit said moving means to move it into engagement with the other of said rolls.
10. The combination of a distributing roll, a fountain roll, a swingably mounted rotatable member arranged to alternately engage said distributing and fountain rolls, a spring tending to move said swingably mounted member into engagement with either of said distributing and fountain rolls, and means for disengaging said swingably mounted member from one of said rolls to permit said spring to move it into engagement with the other of said rolls.
11. The combination with a frame, of a distributing roll, a fountain roll, a swingably mounted rotatable member arranged to alternately engage said rolls, means for swinging said member out of engagement with either of said rolls into engagement with the other of said rolls, and means connected to said frame and the swingable support for said rotatable member for yieldingly holding said member in engagement with one of said rolls.
12. The combination with a frame, of a distributing roll, a fountain roll, a swingably mounted rotatable member arranged to alternately engage said rolls, and means, including a spring connected to said frame and the swingable support for said rotatable member for swinging said member out of engagement with either of said rolls into engagement with the other of said rolls.
13. The combination with a fountain roll and a distributing roll, of a swingable support carrying a member arranged to alternately engage said rolls, a spring connected with said support in correlation with its pivot to act on said support when the latter is swung in either direction about its pivot,

and means for swinging said support in one direction about its pivot.

14. The combination with a fountain roll and a distributing roll, of a swingable support carrying a member arranged to alternately engage said rolls, a spring connected with said support in correlation with its pivot to act on said support when the latter is swung in either direction about its pivot, and means for swinging said support in either direction about its pivot.

15. In an inking device, the combination of a roll, a blade engaging the roll, and plates engaging the opposite ends of said roll and blade and cooperating therewith to form a fountain, the free end of each plate being curved inwardly to deflect the ink away from the adjacent end of the roll.

16. In mechanism of the class described, the combination with a frame, a source of ink supply and an ink distributing element, of a support pivoted to said frame, and

carrying a member arranged to alternately engage with said source of ink supply and said ink distributing element, a spring connected at one end to said frame, a connection between the opposite end of the spring and said support and movable therewith, whereby the spring acts on said support whenever it is moved to either side of a line passing through the axes of the pivot for said support and the connection for the spring with said frame to cause engagement of said member with said source of ink supply or said distributing element, and means for moving said support about its pivot in either direction.

In testimony whereof, I hereunto set my hand this 27 day of October, 1913.

ARTHUR D. SABORSKY.

In presence of—

W.M. J. KLOTZBACH,
W.M. M. MONROE.

Copies of this patent may be obtained for five cents each, by addressing the "Commissioner of Patents, Washington, D. C."

It is hereby certified that in Letters Patent No. 1,282,466, granted October 22, 1918, upon the application of Arthur D. Saborsky, of Lakewood, Ohio, for an improvement in "Inking Devices for Printing-Machines," errors appear in the printed specification requiring correction as follows: Page 3, lines 64, claim 7, strike out the word "of", second occurrence; same page and claim, line 65, before the article "a" insert the word *of*; and line 68, before the word "plates" insert the words *springs engaging said*; and that the said Letters Patent should be read with these corrections therein that the same may conform to the record of the case in the Patent Office.

Signed and sealed this 26th day of November, A. D., 1918.

[SEAL.]

R. F. WHITEHEAD,

Cl. 101—350.

Acting Commissioner of Patents.
